ENGINE STARTING MECHANISM

Howard Baer, Jersey City, N. J., assignor to
 Eclipse Aviation Corporation, East Orange,
 N. J., a corporation of New Jersey

Application June 10, 1937, Serial No. 147,570

2 Claims. (Cl. 121—37)

This invention relates to starting devices for internal combustion engines.

One of the objects of the invention is to provide an engine starter of the torque applying type embodying novel means for producing engagement with and transmission of torque to a member of the engine to be started.

A further object of the invention is to provide in a starting device of the foregoing character, novel means for converting an axially directed pressure into a rotation producing force whereby the axial movement of the driving member is translated to the engine cranking member.

A further object of the invention is to provide a novel starting mechanism of the type employing a plurality of power actuated pistons one of which operates to produce engagement between the starting mechanism and a member of the engine to be started, and the other of which operates to impart a cranking torque to the engine engaging member.

Another object of the invention is to provide a multiple power member starter of the foregoing character which makes it possible, by the use of a novel construction, to obtain a quicker and more certain inter-engagement between the teeth of the engine engaging member and the engaged member of the engine, prior to any appreciable axial movement of the larger of the two power actuated pistons above referred to.

A further object is to combine the "double screw" teaching of Adolf König, in his German Patent No. 444,546, with the above described multiple piston concept of operation.

Other objects and advantages to be derived from the use of the invention reside in the specific construction, combination and interrelation of parts whereby a compact, efficient and easily operated and maintained unit is produced, all of which objects and advantages will appear more clearly upon an inspection of the following specification, with reference to the accompanying drawing illustrating the preferred embodiment of the invention. It is to be expressly understood however, that the said drawing is for the purpose of illustration only and is not to be construed as a definition of the limits of the invention, reference being had to the appended claims for this purpose.

In the drawing, wherein like reference characters refer to like parts throughout the several views:

Fig. 1 is a longitudinal axial section through a device embodying the invention;

Fig. 2 is a slightly reduced end view partly in

section, and taken along line 2—2 of Fig. 1; and Fig. 3 is a fragmentary view along the inner assembly of Fig. 1.

With reference to the drawing, and more particularly to Fig. 1, the piston actuated unit is contained within a sectional housing including cylindrical parts 17 and 10, the latter having a flange 12 by which it is secured to the engine crankcase 13 as by bolts 14, the flange being conveniently of a size standardized for aircraft engine starters. The engine crankshaft, or other drive shaft (not shown) is provided with a clutch element 11 engageable by the piston actuated clutch element 15 as will be later more fully described.

Cylinder 17 has a cup-shaped head 18, with a cylindrical portion 19 to receive piston 23, said portion 19 being externally threaded to coact with a correspondingly internally threaded section 20 of a triple section intermediate transmission member A consisting of parts 20, 21 and 24. A second screw 22 is drivably connected with the threaded section 24 by helical grooves or threads 29 and 31 which permit the axial travel of the piston 23 but cause rotation of the screw 22 because of friction reducing balls 36 assembled in cage 35 and inserted in the helical grooves 29 and 31, stops 28a and 28b serving to limit the endwise movement of the cage. For a similar purpose threaded sections 19 and 20 receive balls 6 of a similar cage 7, retained within its limits of movement by stops 8 and 9, corresponding to stops 28a and 28b, respectively.

An anti-friction thrust bearing 32 is preferably interposed between a flanged skirt 34 on the rear end of a spacer member (34b) and an inwardly extending circular portion 33 of the body 10, the said bearing 32 acting to take the axial thrust to which the inwardly extending rim 34a, on the forward end of the spacer member, is subjected. A spring 37 has one end resting against the closure plate 16 of the cylinder 17, and its opposite end abuts the thrust ring 38, which in effect, through the sleeve 24, abuts the outer race 39 of a ball-bearing assembly 40 axially movable with but rotatably free of the piston 23, the intervening bearing balls 40 facilitating free rotation of outer race 39 of the bearing, while the thrust ring 38 being possibly constrained to rotation by the natural twisting tendency of a spring such as the spring 37, as the latter is compressed in the forward travel of the piston. Piston rings 41 insure against the loss of pressure as the piston moves forward.

and also yieldably oppose any tendency towards rotation of the piston.

Due to the bolted split clamp connection 42 between the cylinder 17 and the body flange 10a, the former may be quickly detached for removing any fouling that may occur where combustible cartridges are used as the source of fluid pressure to move the piston 23.

The present invention, as above indicated, includes improved means for automatically controlling both the meshing of parts 15 and 11, and the exhaust of the fluid pressure from the cylinder upon completion of the cranking operation. This combined meshing and exhaust control may be effected by providing a path along which the pressure fluid may flow to act directly and immediately upon the head portion 22a of the sleeve 22 whereby said sleeve 22 may move axially forward prior to and independently of the beginning of axial movement of the main piston 23, as is explained more fully hereinafter—the said head portion 22a of the sleeve 22 thus constituting, in effect, a separate piston with exposed surface area greater than the initial exposed surface areas of the piston 23 and parts integrated therewith—the annular boss 91 of the cylinder head serving to "block off" the major portion of the piston area with the parts in the relative positions shown in the drawing. Forward movement of piston 22a tends to compress the spring 42a to transmit, by way of said spring, a forward meshing movement to the clutch member 15, thereby bringing the latter into operative engagement with the engine member 11. As shown, the pressure fluid path leading to the piston 22a includes openings formed by cutting away the flanged forward end of the exhaust valve 43 to form fingers 44, whereby the fluid entering through conduits 61 and 62 (Fig. 2) to annular chamber 45, may instantly pass directly into a long annular chamber between the rod 46 and the tube 47, which constitutes a centrally disposed extension of the piston 23, to which piston the flanged rear end of the tube 47 is connected by suitable screws 48 or equivalent means, as illustrated; the forward end of the annular chamber thus formed having communication with the bore of the sleeve 22 by virtue of the area surrounding radial projections 49 formed on the forward end of the rod 46, and also by virtue of the passage-way continuing through the thickened forward portion 50 of the tube 47. This forward portion 50 is provided with sealing rings 51 which prevent seepage of fluid or particles contained therein backwardly into the space surrounding the tube 47, while at the same time facilitating and permitting free sliding movement of the tube within the bore of sleeve 22 as the piston 23 moves forward in the cylinder 19. The valve 43 is carried by the rod 46 and is of such a length that with the parts in the positions indicated in Fig. 1, a collar 52 extending inwardly of piston 23 will bear against the fingers 44 on the valve 43 to hold said valve on the seat 53a formed in the head 53. At the commencement of an operative cycle of the motor, such as is occasioned by the delivery of fluid pressure to the chamber 45, this fluid pressure will tend to maintain the exhaust valve 43 closed; but as the piston nearly reaches the end of its movement, the collar 52 will be brought into engagement with the projections 49 to unseat the exhaust valve 43. In this connection the central opening in collar 52 is so formed as to provide a plurality of corresponding inwardly ex-

tending projections or fingers for abutment with the radial projections 49 of the rod 46 as the piston 23 approaches the end of its stroke, while at the same time this construction permits constant clearance between the said collar 52 and the rod 46 (as shown clearly in Fig. 1) whereby the pressure fluid is always free to pass between the chamber 45 and the bore of sleeve 22, passage being first from chamber 45 to the bore 22 (at the beginning of the cycle of operations) and subsequently in the reverse direction to allow the pressure fluid to be exhausted in response to the opening of the exhaust valve 43—that is, its removal from its seat in the housing 53—by the engagement of the collar 52 with the projections 49 at the end of the stroke of the piston 23 as above described. The exhaust valve having been thus unseated, the bead 54 thereon will engage the conical end of valve guide 55 to yieldably hold the valve in the open position, to permit exhaust by way of outlet passage 57, outlet ports 58 in the cage 59, and exhaust pipe 60.

The piston having completed its operative stroke, and the exhaust valve having been opened, the piston will be urged on its return stroke by the coil spring 37. During this return movement, the exhaust valve being held open, the cylinder will be effectively scavenged. Due to the action of the parts 54 and 55 the valve will remain open until such time as the piston collar 52 is brought to bear against the fingers 44 at the end of valve stem 43 for again seating the valve. This insures closing movement of the valve at the time the piston has substantially completed its return movement. It is thus apparent that the exhaust means is of such construction as to remain open during the major portion of the return stroke of the piston so as to insure substantially complete scavenging. In order to permit the movement of the sleeve 22 for the purpose of meshing the parts 15 and 11 independently of the movement of the piston 23—without at the same time creating too severe an axial thrust on the driving sleeve 24 with which the said driven sleeve 22 is threadedly engaged, the ball-cage assembly 35 is preferably of a length somewhat less than the distance between retainer rings 28b and 28a whereby forward movement of the sleeve 22 to the extent necessary to induce complete mesh between parts 15 and 11 occurs prior to taking up of the thread-clearance between the end-balls 36 on the one hand, and the retainer rings 28b and 28a on the other.

If during this meshing movement a collision should occur between the corners of the teeth of the two parts 15 and 11 thus temporarily interfering with full engagement thereof the piston 22a and sleeve 22 will nevertheless continue to move axially forward in response to the urge of the pressure fluid which has entered its bore by way of the communicating passage-ways above described, such continued forward movement of the piston 22a being possible because of the clearance between the forward end of the said piston and the jaw 15 to which the forward end is splined as indicated at 56, the spring 42a also being sufficiently compressible to permit such relative axial movement. During this relative axial movement a certain amount of rotary movement reverse to the rotary movement of the cranking will also occur due to the effect of the relatively stationary threads 31 of the outer sleeve 24 upon those of the sleeve 22 and such rotary movement will therefore relieve the condi-

tion of cornered tooth contact, whereupon spring 42a will expand from its compressed condition and thereby press the jaw member 15 into full engagement with the engine member 11.

5 The triple section transmission member A, although of novel construction, embodies the principle of the König patent above identified in that it serves to increase the amount of rotation of the driven screw 22 by reason of its coaction with the threaded extension 19 of the cylinder head 18. This threaded extension 19 therefore corresponds to the threaded extension "r" of the König patent, in that it remains in the rear of the piston 23 as the piston advances (as is also true 15 of König's part r) rather than being disposed in advance of the piston at all times, as in certain other devices now in use. On the other hand it differs from König in the sense that it permits the use of a more nearly solid piston surface 20 area.

In order to secure the increased amount of rotation referred to in the preceding paragraph, the helical grooves in section 20 of the member A are pitched in the opposite direction from those of section 24; the elements 19 and 22 being threaded to correspond to the helical grooves or threads of sections 20 and 24, respectively.

What is claimed is:

1. In a motor, the combination with an externally threaded cylindrical element, fixed against rotation and provided with a smooth

inner surface, of rotatable driven means, and means for driving said rotatable driven means, said driving means including a piston movable along the smooth inner surface of said fixed cylindrical element, a part threadedly engageable with the threaded outer surface of said fixed cylindrical element, and means including a member moved by the piston and integrated with said last-named part for causing the longitudinal movement of said piston to be translated into a 10 rotary movement of said driven means.

2. In a motor, rotatable driven means, longitudinally moving driving means having an annular pocket therein, said driving means also having helical grooves along one side of said annular pocket, a plurality of balls disposed in said helical grooves, means including a stationary smooth-bored cylindrical element extending into said annular pocket and a piston slidable along said smooth-bored cylindrical element for imparting longitudinal movement to the driving means, means including a helically grooved surface integral with said smooth-bored cylindrical element for coaction with said balls and first-named helical grooves to cause said driving 25 means to rotate as the latter moves longitudinally, and means for transmitting said rotation to the driven means at an increased rate of speed.

HOWARD BAER.
